MECHANISM FOR FEEDING TO, AND CLAMPING BODIES IN, MACHINES

Clifford H. Green, Paris Township, Kent County, Mich., assignor, by means assignments, to Automatic Musical Company, a Corporation of Michigan

Application November 11, 1932
Serial No. 642,318

14 Claims. (Cl. 274—45)

The present invention relates to mechanism for feeding elongated bodies to a machine and releasably clamping the same thereon; and its object is, generally, to provide an improved mechanism of that character; and more particularly, to provide such a mechanism comprising a rotatable feeding carrier for said bodies, devices for clamping the same on the machine and means operating in proper sequence for actuating the parts; and further, to provide improved specific means for this purpose.

These and any other objects hereinafter appearing are attained by, and the invention finds preferable embodiment in, the illustrative mechanism particularly described in the body of this specification and illustrated by the accompanying drawings, in which:

Figure 1 is an elevational front view of mechanism for successively feeding elongated bodies (as the needles or styli of a graphophone) and for releasably clamping the same to a machine part (as to the tone arm of the graphophone), certain parts being sectioned on lines 1—1 and 1a—1a of Figures 2 and 5 respectively;

Figure 2 is an elevational side view thereof, a portion being broken away;

Figure 3 is a top plan view of said mechanism partially sectioned on line 3—3 of Figure 1;

Figure 4 is an elevational view of parts of said mechanism partially sectioned on line 4—4 of Figure 1;

Figure 5 is a sectional view of certain parts of said mechanism taken on line 5—5 of Figure 1;

Figure 6 is a sectional view of certain parts of said mechanism taken on line 6—6 of Figure 1;

Figure 7 is a top plan view of certain parts of said mechanism, partially broken away and showing a lever sectioned on line 7—7 of Figure 2;

Figure 8 is a detail view of parts of said mechanism sectioned on line 8—8 of Figure 3;

Figure 9 is a bottom end view of a vertically movable rod with connected parts;

Figures 10, 11 and 12 are end views of a shaft and connected parts, showing the same in different turned positions.

The particular embodiment of the invention illustrated by these drawings is employed for feeding to, and clamping in, a graphophone's tone arm 1 its elongated cylindrical needles or styli 2. These needles in vertical position are removably held in holes 3 circularly disposed in series in the upper side of a carrier 4 which is

turnable in its bearing 5 in the upper end of a squared rod 6 vertically slidable in a bearing 7 in the mechanism's frame 8. In Figure 1, this carrier is shown in solid lines in its lowered position from which it is raised to dotted line 60 position to insert into the socket 9 of the tone arm the particular needle which has been brought, by a previous turning movement of the carrier, into registration with this socket. The carrier is raised to its dotted line position (Figure 1) by the turning of a disk 10 having in its inner side a cam groove 11 in which travels the roll 12 on an arm of the lever 13 fulcrumed at 14, whose other arm 15 is connected to a link 16 pivoted at 17 on said squared rod 6.

As seen in Figure 1, a worn needle 2¹ is about to be released from the tone arm and replaced with a new needle 2 taken from the carrier. To do this, the cycle of the mechanism's operation is as follows: The disk 10 is rotated so that the peripheral cam groove 38 moves the roll 37 on one arm 36 of a lever 31 (fulcrumed at 32) into the portion 60 of said groove 38 and thereby slides the shaft 27 (rotatably mounted at 61 on the frame) toward the left hand side of Figures 1 and 3 thereby causing the kerf 39 in the end of said shaft's member 40 to engage the diametrical rib 41 on the end or head 42 of a set screw 43 threaded in the tone arm and extending into its socket 9 and into engagement with the needle 2¹ to clamp the same therein. The shaft 27, acting as a screw driver, is rotated to turn said screw sufficiently to release this needle 2¹, by means of the rotation of said disk on whose crank wrist pin 25 is carried a rack 24 meshing 90 with a gear 26 to turn said shaft 27. The needle 2¹ thus released falls out of said socket to be discarded.

The further turning movement of disk 10 causes the roll 12 to move out of the dwell 18 of cam groove 11 and thereby raises the carrier and inserts a needle 2 into the now empty socket. While the carrier is thus in raised position the further rotation of disk 10 carries the wrist pin 25 past its highest point and causes the rack to move reversely thus turning the shaft 27 reversely, which movement turns the screw 43 reversely and into binding engagement with the needle which has just been inserted into the socket, whereupon said disk's further turning movement causes the roll 12 to pass into the dwell 18 and restores the parts to initial position shown in solid lines in Figure 1.

For the purpose of cushioning the action, the gear 26 has a pin 29 and the shaft 27 has a 110

pin 30 connected by a coiled spring 28. Normally these pins are in the abutting relation seen in Figures 10 and 11 while the gear rotates the shaft yieldingly by the spring in the 5 direction of the arrows and sufficiently to turn the screw into binding engagement with the needle just inserted into the socket.

To allow for inaccuracies in construction or 10 operation, the shaft may, after the screw is turned down, further turn from the position seen in Figure 11 to that shown in Figure 12, such movement further tensioning the spring. The turning movement of the shaft with its member 40 in contact with the screw's rib 41, 15 but before the rib 41 is in alignment and engagement with the kerf 39 is thus permitted, and is also permitted by the axial movement of said member splined to said shaft by its screw key 44 engaging in the shaft's longitudinal 20 groove 45, said member being pressed outwardly by the spring 46. At a point in the lowering movement of the carrier, one of the circularly disposed teeth 19 on its under side engages the pawl arm 20 of a bell crank lever 21 fulcrumed 25 at 22, and the continued downward movement of the carrier in such engagement causes the carrier to turn a sufficient distance to bring the next succeeding needle 2 held thereby into registration with said socket for insertion thereinto on the next rising movement of the carrier. The carrier is held against reverse turning by the detent 51 pressed into engagement with one 30 of said teeth by the spring 52.

The disk 10 may be rotated to operate the said 35 mechanism by any suitable means, as by connections with the driving or operating means of the graphophone or other machine to which said mechanism is applied, and at intervals for replacing such worn elongated bodies, as the 40 worn needles of a graphophone. This disk as shown is in the form of a gear meshing with a driving gear 49. The rack 24 bears slidably in a turnably mounted block 50. The wrist pin 25 is carried by a block 53 slideable to adjusted 45 positions in a diametrical groove 54 in the disk's portion 23 and held in such positions by the nut 56. When a needle 2¹ is released from said socket it falls into a chute 47. This chute has 50 a springable upper end or trough 48 (shown in solid lines in its normal position) in which the discarded needle 2¹ is guided into the chute. Thereafter, the rising movement of the carrier to insert a new needle into the socket slides at its 55 edge along said end 48 and springs it to dotted line position (shown in Figure 1) out of the way of said new needle. In the graphophone's operative movement its tone arm swings past its position in which the needle is inserted into its 60 socket and the carrier is lowered to permit said end 48 to spring back to its solid line position.

This mechanism may manifestly be employed for many other purposes and connections than to feed needles to a graphophone's tone arm and to clamp the same thereto.

I regard it advisable that the parts be so relatively adjusted that the shaft 27 is turned a part revolution before it is moved axially toward the screw 43.

The invention being intended to be pointed out in the claims, is not to be limited to or by details of construction of any particular embodiment thereof illustrated by the drawings or hereinbefore described.

I claim:

1. In mechanism for feeding elongated bodies to and clamping the same in a machine part having an elongated socket adapted to receive said bodies, comprising: a carrier releasably holding said bodies in spaced positions thereon axially parallel with said socket, the carrier being movable in a direction transaxial of the socket to feed said bodies severally to position axially aligned with the socket, and movable axially to insert said bodies into the socket; means for clamping said bodies in their inserted position.

2. In mechanism for feeding elongated bodies to and clamping the same in a machine part having an elongated socket adapted to receive said bodies, comprising: a carrier releasably holding said bodies in spaced positions thereon axially parallel with said socket, the carrier being movable in a direction transaxial of the socket to feed said bodies severally to position axially aligned with the socket, and movable axially to insert said bodies into the socket; means for so moving the carrier; means operable in connection with and in timed sequence relatively to said first-mentioned means for clamping said bodies in their inserted position.

3. In mechanism for feeding elongated bodies to and clamping the same in a machine part having an elongated socket adapted to receive said bodies, comprising: a carrier releasably holding said bodies circularly disposed in spaced positions thereon axially parallel with said socket, the carrier being turnable in a direction transaxial of the socket to feed said bodies severally to position axially aligned with the socket, and movable axially to insert said bodies into the socket; means for clamping said bodies in their inserted position.

4. In mechanism for feeding elongated bodies to and clamping the same in a machine part having an elongated socket adapted to receive said bodies provided with a binding screw therefor, comprising: a carrier releasably holding said bodies circularly disposed in spaced positions thereon axially parallel with said socket, the carrier being turnable in a direction transverse of the socket to feed said bodies severally to position axially aligned with the socket, and movable axially to insert said bodies into the socket; a screw-driving shaft axially movable to and from operative engagement with said screw to turn the same; a rotatable driving element; connections between said element and the carrier for moving the same axially; connections between said element and said shaft for rotating the same.

5. In mechanism for feeding elongated bodies to and clamping the same in a machine part having an elongated socket adapted to receive said bodies provided with a binding screw therefor, comprising: a carrier releasably holding said bodies circularly disposed in spaced positions thereon axially parallel with said socket, the carrier being turnable in a direction transverse of the socket to feed said bodies severally to position axially aligned with the socket, and movable axially to insert said bodies into the socket; a screw-driving shaft axially movable to and from operative engagement with said screw to turn the same; a rotatable driving element; connections between said element and the carrier for moving the same axially; connections between said element and said shaft for rotat-

- ing the same; connections between said element and the shaft for moving the same axially. 80
6. In mechanism for feeding elongated bodies to and clamping the same in a machine part 5 having an elongated socket adapted to receive said bodies provided with a binding screw therefor, comprising: a carrier releasably holding said bodies circularly disposed in spaced positions thereon axially parallel with said socket, the carrier being turnable in a direction transverse of the socket to feed said bodies severally to position axially aligned with the socket, and movable axially to insert said bodies into the socket; a screw-driving shaft axially movable to and from operative engagement with said screw to turn the same; a rotatable driving element; connections between said element and the carrier for moving the same axially; connections between said element and said shaft for rotating the same; means engaging the carrier for rotating the same step by step by the carrier's axial movement in one direction. 85
7. In mechanism for feeding elongated bodies to and clamping the same in a machine part 25 having an elongated socket adapted to receive said bodies provided with a binding screw therefor, comprising: a carrier releasably holding said bodies circularly disposed in spaced positions thereon axially parallel with said socket, the carrier being turnable in a direction transverse of the socket to feed said bodies severally to position axially aligned with the socket, and movable axially to insert said bodies into the socket; a screw-driving shaft axially movable to and from operative engagement with the screw; a gear on said shaft for turning the same; a rotatable driving element; connections between said element and the carrier for moving the same axially; a rack mounted eccentrically on 90 said element and meshing with the gear for turning the shaft by the rack's movement in one direction and turning the shaft reversely by the rack's movement in the opposite direction. 95
8. In mechanism for feeding elongated bodies to and clamping the same in a machine part 30 having an elongated socket adapted to receive said bodies provided with a binding screw therefor, comprising: a carrier releasably holding said bodies circularly disposed in spaced positions thereon axially parallel with said socket, the carrier being turnable in a direction transverse of the socket to feed said bodies severally to position axially aligned with the socket, and movable axially to insert said bodies into the socket; a screw-driving shaft axially movable to and from operative engagement with the screw; a gear turnable on the shaft and yieldingly connected therewith to turn the same; a rotatable driving element; connections between said element and the carrier for moving the same axially; a rack mounted eccentrically on 100 said element and meshing with the gear for turning the shaft. 105
10. In mechanism for feeding elongated bodies to and clamping the same in a machine part 35 having an elongated socket adapted to receive said bodies provided with a binding screw therefor, comprising: a carrier releasably holding said bodies circularly disposed in spaced positions thereon axially parallel with said socket, the carrier being turnable in a direction transverse of the socket to feed said bodies severally to position axially aligned with the socket, and movable axially to insert said bodies into the socket; a screw-driving shaft axially movable to and from operative engagement with the screw; a gear turnable on the shaft and yieldingly connected therewith to turn the same; a rotatable driving element; connections between said element and the carrier for moving the same axially; a rack mounted eccentrically on 110 said element and meshing with the gear for turning the shaft by the rack's movement in one direction and turning the shaft reversely by the rack's movement in the opposite direction. 115
11. In mechanism for feeding elongated bodies to and clamping the same in a machine part 40 having an elongated socket adapted to receive said bodies, comprising: a carrier releasably holding said bodies in spaced positions thereon axially parallel with said socket, the carrier being movable in a direction transaxial of the socket to feed said bodies severally to position axially aligned with the socket, and movable axially to insert said bodies into the socket; means for clamping said bodies in their inserted position and for releasing said bodies by the opposite movement of said means. 120
12. In mechanism for feeding elongated bodies to and clamping the same in a machine part 45 having an elongated socket adapted to receive said bodies, comprising: a carrier releasably holding said bodies circularly disposed in spaced positions thereon axially parallel with said socket, the carrier being turnable in a direction transaxial of the socket to feed said bodies severally to position axially aligned with the socket, and movable axially to insert said bodies into the socket; means for clamping said bodies in their inserted position; a discharge chute in 125 position receiving such bodies from the socket and movable from said position by the axial movement of the carrier. 130
13. In mechanism for feeding elongated bodies to and clamping the same in a machine part 50 having an elongated socket adapted to receive said bodies provided with a binding screw therefor, comprising: a carrier releasably holding said bodies circularly disposed in spaced positions thereon axially parallel with said socket, the carrier being turnable in a direction transverse of the socket to feed said bodies severally to position axially aligned with the socket, and movable axially to insert said bodies into the socket; a screw-driving shaft axially movable to and from operative engagement with said screw to turn the same; a rotatable driving element; connections between said element and the carrier for moving the same axially; connections between said element and the carrier for mov- 135
